Attorney.

UNITED STATES PATENT OFFICE.

RICHARD A. JOHNSTON, OF NEW YORK, N. Y., ASSIGNOR TO BARRON G. COLLIER, INC.,
OF NEW YORK, N. Y.

FRAME FOR ADVERTISING CARDS.

1,424,570.

Specification of Letters Patent. Patented Aug. 1, 1922.

Application filed October 12, 1921. Serial No. 507,230.

To all whom it may concern:

Be it known that RICHARD A. JOHNSTON, a citizen of the United States of America, residing at New York, in the county of New 5 York and State of New York, has invented certain new and useful Improvements in Frames for Advertising Cards, of which the following is a specification.

My invention relates to a frame for holding advertising cards adapted to be placed in the ends of trolley or other passenger cars, more particularly between the end doors and sides of the cars, and is an improvement on my prior patent No. 1382646.

15 The object of the invention is to produce a frame in which one or a plurality of cards may be conveniently inserted and having a slideable top attached to the main section of the frame adapted to be opened to permit 20 the insertion of a card without the necessity of bending or twisting same and thereafter to be closed to securely hold it in position.

A further object of the invention is to provide means for preventing the cards from 25 buckling or bulging outwardly after they have been positioned in the frame.

Other and further objects of the invention will be apparent as the description is proceeded with.

30 Referring to the drawing wherein a preferred embodiment of my invention is illustrated:

Figure 1 is a face view of my invention;

Figure 2 is a sectional view taken on the 35 line 2—2 Figure 1;

Figure 3 is a section on the line 3—3 Figure 1; and

Figure 4 is a section on the line 4—4 of 40 Figure 1.

Figure 5, is a section on the line 5—5 of Figure 1.

Referring more specifically to the drawings, 5 denotes a preferably metallic board or frame having its side and bottom edges 6 inwardly turned or rolled to form a beading or border and also to provide side grooves 7 for slidably receiving the end edges of the advertising cards (not shown). The opening 8 in the top of the frame through which 10 the cards may be readily inserted without bending, is normally closed by means of the 15 slideable closure member 9 having straight side edges 10 adapted to slide in the upper portions of the grooves 7, the top edge 11 of 20 the closure member 9 being rolled inwardly

to simulate the appearance of the side and bottom edges of the frame 5. It is not necessary to completely remove the closure member to enable the user to insert the cards, but merely to slide the former outwardly or upwardly a slight distance as side grooves 7 are sufficiently wide to accommodate both closure member and cards. This sliding movement of the closure member is limited by means of lugs 12, preferably 65 punched from the closure member, operating in slots 13 formed in the upper portion of the frame 5. In order to completely remove the closure member, or when inserting the same in place, the lugs 12 must of course be 70 forced out of the slots 13.

One or more cross pieces 14 preferably of sheet metal doubled in the direction of their length and bent to form top and bottom side grooves 15, have their end edges 16 slidably 75 mounted in the side grooves 7 of the frame 5. The cross pieces serve as partitions between the different cards, which are adapted to be slidably carried on the face of the frame or board 5 with their top and bottom edges 80 firmly seated in the respective grooves 15. Any number of cross pieces or partitions may be used according to the number of cards to be employed, or they may be eliminated where a single card is displayed. 85 These partitions may be easily removed by slightly raising the closure member 9 and sliding the former out through end of grooves 7.

Any suitable means may be employed to 90 attach the frame or board 5 to the car, such as screws or the like (not shown) adapted to pass through openings 16'.

It has been found in actual practice where one or more of the cross pieces 14 are dispensed with and a correspondingly large advertising card (not shown) is inserted, that the card will sometimes bulge or buckle outwardly at the middle. To obviate this I provide the metallic board or frame 5 with an 100 insert 20 of wood or other suitable material adapted to retain the point of a headed pin 21 when the pin is pressed through the advertising card into the insert 20. As will be seen from an inspection of Figure 5, the insert is retained in position by passing the same through vertically disposed spaced parallel slits 22, it being understood that edges or marginal side walls 23 of these slits are bent outwardly and that the portion 24 of 110

the metallic board or back 5 is bent or pressed rearwardly to a slight degree to facilitate insertion of the wooden member or insert 20.

While I have shown but one insert 20, it is obvious that where more than one advertising card is used in the frame, an insert 20 for each advertising card may be employed.

Having thus described my invention:

What I claim is:

- 10 1. A street car advertising frame comprising a rectangular metallic sheet provided with means for receiving and retaining the edges of an advertising card, and means for securing the intermediate portion of said advertising card to the said sheet whereby bulging of said advertising card will be pre-

vented, said last mentioned means comprising a wooden insert, means on said metallic sheet for retaining said insert, and means for securing the card to said insert. 20

2. A street car advertising frame comprising a metallic sheet provided with marginal portions for receiving and retaining the marginal edges of an advertising card, said sheet formed with spaced slits intermediate 25 the sides thereof, a wooden insert in said slits, and means for securing the intermediate portion of said advertising card to said wooden insert.

In testimony whereof I affix my signature. 30

RICHARD A. JOHNSTON.
